AIR CIRCULATION CONTROL

Alfred G. Janos, Erie, Pa., assignor to General Electric Company, a corporation of New York

Application May 25, 1949, Serial No. 95,191

4 Claims. (Cl. 62—4)

1

My invention relates to refrigerators and more particularly to arrangements for controlling air circulation within refrigerator cabinets.

It is an object of my invention to provide an improved arrangement for controlling air circulation within a refrigerator cabinet.

It is a further object of my invention to provide an improved arrangement for controlling air circulation in a refrigerator cabinet wherein circulation of air is reduced when the refrigerating apparatus is not operating.

Further objects and advantages of my invention will become apparent as the following description proceeds, and the features of novelty which characterize my invention will be pointed out with particularity in the claims annexed to forming part of this specification.

In carrying out the objects of my invention a damper is provided for controlling the circulation of air through a passage within a refrigerator cabinet. The position of this damper is controlled by a solenoid energized in such a manner that the damper is open when the condensing unit is operating and closed when the condensing unit is not operating.

For a better understanding of my invention reference may be had to the accompanying drawing in which Fig. 1 is a front elevation view of a portion of a refrigerator cabinet incorporating my invention; Fig. 2 is a sectional side elevation view of the portion of a refrigerator cabinet; Fig. 3 is a schematic circuit diagram; Fig. 4 shows a modified form of my invention; and Fig. 5 is a schematic circuit diagram applicable to the form shown in Fig. 4.

Referring now to Figs. 1 and 2, there is shown a portion of a refrigerator cabinet 1 having a door 2 hinged thereto. The cabinet 1 includes an outer wall or shell 3 and a spaced inner wall or liner 4. The space between the inner and outer walls is filled with a suitable heat-insulating material 5. A breaker strip 6 is provided for closing the space between the inner and outer walls adjacent the door opening of the cabinet.

The liner 4 is shaped to define a food storage compartment 7 within the cabinet. In order to refrigerate this compartment an evaporator or cooling unit 8 is provided. This evaporator is positioned near the top of the food storage compartment 7 and is supported from the liner 4 by suitable brackets 9. The cooling unit 8 may be refrigerated by circulating vaporizable refrigerant through the evaporator by a suitable condensing unit (not shown) in the conventional manner. Of course, the invention is equally applicable to apparatus wherein a liquid refrigerant is circulated through the cooling unit by any suitable liquid-circulating apparatus. The evaporator 8 is shaped to provide a chamber for storing frozen food therein, and this chamber

2

is closed by a door 10 hinged at 11 to the evaporator. A trough 12 extends across the front of the cabinet for catching drip from the door of the evaporator.

5 The air within the food storage compartment 7 is cooled as a result of natural circulation of the air over the evaporator 8. For example, the air may rise along the front portion of the cabinet, circulate rearwardly over the evaporator, and then descend in the rearward portion of the cabinet. To control this circulation of air a baffle and damper arrangement is provided. The baffle includes a drip tray 13 which is supported on suitable guides one of which is shown 10 at 14. A conventional receptacle 15 is also shown mounted on suitable guides, one of which is shown at 16, but this receptacle may be omitted, if desired, with no effect on the operation of the apparatus included in my invention. 15 The drip tray 13 extends across the width of the food storage compartment 7, and the drip tray is made imperforate so that air cannot pass through the tray. Since the baffle extends the full width of the food storage compartment air 20 may pass between the lower portion of the food storage compartment and the cooling unit 3 only adjacent the front and the back of the baffle. As best shown in Fig. 2 the forward edge of the baffle is spaced from the door 2 so as to provide 25 a passage 17 for air. The rear edge of the baffle is spaced from the back wall 18 of the liner 4, providing a passage 19 for the circulation of air from the region of the evaporator 8 to the lower part of the food storage compartment.

30 To control the circulation of air through the passage 19, a damper 20 is provided. The damper 20 is hinged at 21 to a bracket 22 which is secured by screws or other suitable fastening devices to the liner 4, one such screw being indicated at 23. The baffle further includes a horizontally extending bracket 24 which is secured in any suitable manner, as by welding, to a support 25, and the forward end of the damper 20 is adapted to engage the bracket 24. A lip 26 of the bracket 24 extends over the rear edge of the drip tray. It will be apparent that, if desired, the bracket 24 could be omitted and the damper 20 could be arranged to engage directly the rear edge of the drip tray 13. However, since 35 the position of the drip tray 13 may vary from time to time it is preferable to utilize a baffle which includes not only the drip tray 13 but also the horizontally extending bracket 24. Moreover, although a drip tray has been shown as 40 constituting the major portion of the baffle, any imperforate structure disposed generally horizontally beneath the evaporator could be employed in lieu of the drip tray.

45 The damper 20 is adapted to occupy one position, as illustrated in Fig. 2, wherein the damper

closes the passage 19 and reduces or blocks the circulation of air within the food storage compartment. The damper is adapted to occupy a second and substantially vertical position adjacent the rear wall 18 of the liner 4 to allow circulation of air through the passage 19. In order to shift the damper to this second position a solenoid 27 is provided, and the solenoid is mounted by screws 28, or other suitable fastening devices, on the bracket 22. An armature 29, which is controlled by the solenoid 27, is connected by a hinged link 30 to the forward edge of the damper 20. When the solenoid is energized, the armature 29 is attracted, moving upwardly to the right, and, through the link 30, carrying the damper 20 to the second position generally adjacent the rear wall 18 of the liner 4.

In order to control the energization of the solenoid and, hence, the position of the damper 20, a circuit shown in Fig. 3 is provided. This circuit is arranged so that the damper occupies its closed position when the condensing unit is idle and its open position when the condensing unit is operating. Referring to Fig. 3, power is supplied to the solenoid 27 and to the motor of a condensing unit indicated generally at 31 from power lines 32, 33. The starting and stopping of the condensing unit is controlled in a conventional manner by a temperature-responsive bulb 34 which is positioned adjacent the evaporator 8. The bulb 34 is connected by a tube 35 to a bellows 36. The expansion and contraction of the bellows 36 under the influence of the bulb 34 moves a toggle switch 37 to the closed and open positions respectively to control the supply of power to the condensing unit 31. In the closed position the contact arm of the toggle switch 37 engages a contact 37'; in the open position the movement of the contact arm is limited by a stop 37''. In order to energize the solenoid concurrently with the supplying of power to the condensing unit 31, the solenoid 27 is connected in parallel with the condensing unit 31 by means of conductors 38 and 39.

It can be seen, therefore, that when the evaporator reaches a predetermined maximum temperature, the switch 37 is closed to start operation of the condensing unit 31 for supplying refrigerant to the evaporator 8. At the same time the switch 37 completes a circuit to energize the solenoid 27. The solenoid attracts the armature 29 to open the damper 20 permitting air circulation through the passage 19. Conversely, when the predetermined minimum temperature is reached the contraction of the bellows causes the switch 37 to open concurrently the power circuit to the condensing unit 31 and to the solenoid 27. Upon deenergization of the solenoid the damper 20 falls by gravity to the position shown in Fig. 2, blocking or reducing the circulation of air through the passage 19. Accordingly, by my arrangement, the damper 20 is opened to permit circulation of air within the food storage compartment and over the evaporator whenever power is supplied to the condensing unit for the operation thereof. Conversely, the solenoid is deenergized for moving the damper to its closed position whenever the circuit to the condensing unit is interrupted and the condensing unit is idle. In an ambient temperature of 60° F., for example, the condensing unit would operate only a small portion of the time and, hence, the damper would remain closed a large portion of the time restricting the air circulation within the compartment. In an ambient temperature of

100° F., for example, the condensing unit would operate a much larger portion of the time and, accordingly, the damper would be maintained in its open position a much larger portion of the time permitting increased circulation of air. Since a smaller amount of air circulation is necessary in a room having a temperature of 60° F. than in a room having a temperature of 100° F. in order to adequately refrigerate food stored in the compartment 7, it can be seen that the arrangement described operates in accordance with the general refrigeration requirements.

In Figs. 4 and 5 there is shown a modified form of my invention in which the damper occupies its open position when the solenoid is deenergized and is moved to its closed position when the solenoid is energized. The same numerals have been applied to corresponding parts in Figs. 4 and 5 and in Figs. 1, 2, and 3. Referring now to Fig. 4, a damper 20' is pivotally mounted on the back wall 18 of the liner 4, as indicated at 40. The damper is arranged to move between the open position, indicated by solid lines in Fig. 4, and the closed position, indicated by dotted lines in Fig. 4, wherein the forward edge 41 of the damper engages the bracket portion 24 of the baffle. The solenoid 27 is provided for actuating the damper 20' between its open and closed positions. The solenoid is fastened by screws 28 or other fastening devices to a bracket 22'. The bracket 22' is supported on the liner 4 by screws or other suitable fastening devices, one such screw being indicated at 23. The armature 29 is connected to the damper by the link 30, one end of which is hinged to the armature 29 and the other end of which is hinged to the damper 20'.

The energization of the solenoid 27 and of the condensing unit 31 is controlled, as in the form previously described, by the temperature-responsive bulb 34. This bulb is connected by a tube 35 to the bellows 36. The expansion and contraction of the bellows controls the position of a toggle switch 37. In the form previously described the switch arm concurrently opened and closed the circuits of the condensing unit and of the solenoid. In the present form the switch 37 is arranged so that it alternatively closes a circuit through the solenoid 27 by engaging the contact 42 or closes a circuit through the condensing unit 31 by engaging a contact 43.

The operation of the modified form shown in Figs. 4 and 5 is as follows. When the temperature of the cooling unit or evaporator 8 reaches a predetermined maximum, the switch 37 is moved by expansion of the bellows 36 to the position shown in Fig. 5 wherein a circuit is closed from the power lines 32, 33 through the condensing unit 31. At the same time the contact arm of the switch 37 disengages from the contact 42, breaking the circuit from the power lines 32, 33 through the solenoid 27. Upon the deenergization of the solenoid the armature 29 falls by gravity to the position shown in Fig. 4 and the damper 20' is moved to the solid line position illustrated in Fig. 4, opening the passage 19 and allowing increased air circulation within the cabinet. When the temperature of the evaporator 8 reaches a predetermined minimum the resultant contraction of the bellows shifts the contact arm of the switch 37 out of engagement with the contact 43 and into engagement with the contact 42. This concurrently interrupts the circuit to the condensing unit 31 and closes the circuit to the solenoid 27. When the solenoid 27 is energized the armature 29 is moved upwardly

to the right, thereby, through the link 30, shifting the damper 20' to the closed position indicated by the dotted lines in Fig. 4.

It can be seen, therefore, that, as in the form previously described, the damper is shifted to the open position concurrently with the starting of operation of the condensing unit and the damper is moved to its closed position concurrently with the stopping of the condensing unit. Thus, an increased circulation of air is provided in the cabinet during the time when the condensing unit is operating and a decreased circulation of air is provided when the condensing unit 31 is not operating.

While I have shown and described specific embodiments of my invention, I do not desire my invention to be limited to the particular constructions shown and described, and I intend by the appended claims to cover all modifications within the spirit and scope of my invention.

What I claim as new and desire to secure by Letters Patent of the United States is:

1. In a refrigerator including refrigerant-circulating means, a food storage compartment and a cooling unit, a baffle within the food storage compartment providing a passage for air circulating within said compartment and over the cooling unit, a damper for controlling circulation of air through said passage, a solenoid for controlling said damper, and a single means dependent on the temperature of said cooling unit for starting and stopping said refrigerant-circulating means to maintain a predetermined range of temperature of said cooling unit during normal operation, said single temperature-dependent means actuating said solenoid to open said damper each time the refrigerant-circulating means is started whereby said damper is open at all times that said refrigerant-circulating means is operating.

2. In a refrigerator including refrigerant-circulating means, a food storage compartment and a cooling unit, a baffle within the food storage compartment providing a passage for air circulation within said compartment and over the cooling unit, a damper for controlling circulation of air through said passage, a solenoid for controlling the position of said damper, and a single means dependent on the temperature of said cooling unit for starting and stopping said refrigerant-circulating means to maintain a predetermined range of temperature of said cooling unit during normal operation, said single temperature-dependent means actuating said solenoid to move said damper to its open position for increasing air circulation each time the refrigerant-circulating means is started whereby said damper occupies its open position at all times that said refrigerant-circulating means is operating, said single temperature-dependent means actuating said solenoid to move said damper to its closed position for decreasing air circulation each time said refrigerant-circulating means is stopped whereby said damper occupies its closed position at all times that said refrigerant-circulating means is idle.

3. In a refrigerator including a cooling unit and refrigerant-circulating means, means defining a food storage compartment, the cooling unit being disposed in the upper portion of said compartment, a baffle spaced from the bottom of said cooling unit and extending across the width of said compartment, said baffle extending substan-

tially the entire depth of said compartment and being spaced from the back of said compartment to provide a passage for air circulating within said compartment and over said cooling unit, a damper disposed within said passage for controlling the circulation of air therethrough, a solenoid for controlling the position of said damper, and means dependent on the temperature of said cooling unit for starting and stopping said refrigerant-circulating means to maintain a predetermined range of temperature of said cooling unit during normal operation, said temperature-dependent means energizing said solenoid to move said damper to an open position for increasing the circulation of air each time the refrigerant-circulating means is started whereby said damper occupies an open position at all times that said refrigerant-circulating means is operating, said damper being gravity-biased to a closed position whereby said damper moves to a closed position to reduce circulation of air when said solenoid is deenergized, said temperature-dependent means also being effective to deenergize said solenoid each time said refrigerant-circulating means is stopped whereby said damper occupies a closed position at all times that said refrigerant-circulating means is idle.

4. In a refrigerator including a cooling unit and refrigerant-circulating means, means including a liner for defining a food storage compartment, the cooling unit being disposed in the upper portion of said compartment, a baffle spaced from the bottom of said cooling unit and extending across the width of said compartment, said baffle extending substantially the entire depth of said compartment and being spaced from the back of said liner to provide a passage for air circulating within said compartment and over said cooling unit, a damper hinged adjacent said back of said liner and biased by gravity to engage said baffle for closing said passage to restrict air circulation within said compartment, a solenoid for lifting said damper out of engagement with said baffle to open said passage, and means responsive to the temperature of said cooling unit for starting and stopping said refrigerant-circulating means to maintain a predetermined range of temperature of said cooling unit during normal operation, said temperature-responsive means energizing said solenoid to open said passage each time the refrigerant-circulating means is started whereby said passage is open at all times that said refrigerant-circulating means is operating, said temperature-responsive means deenergizing said solenoid to allow said damper to close said passage by gravity each time said refrigerant-circulating means is stopped to stop operation thereof whereby said passage is closed at all times that said refrigerant-circulating means is idle.
